Inventor,
Edward E. Krayn,

By *Samuel W. Balch*
Attorney.

UNITED STATES PATENT OFFICE

EDWARD E. KRAYN, OF NEW YORK, N. Y., ASSIGNOR TO THE O. M. EDWARDS COMPANY INC., OF SYRACUSE, NEW YORK, A CORPORATION OF NEW YORK.

SASH STARTER AND HOLDER.

Application filed February 11, 1924. Serial No. 691,968.

The sliding window-sashes particularly of railway coaches are of necessity close fitting so that they will effectively exclude dust and gases. In consequence slight warping of the parts causes such windows to stick so that the sashes are moved with difficulty, especially from a closed position when the lower cross bar of the sash is in engagement with the sill.

10 The object of this invention is to provide a device by which mechanical advantage can be brought to bear in sliding the sash, and particularly in starting it from its closed position.

15 In the accompanying sheet of drawings which forms a part of this specification,

Figure 1 shows a portion of a window-sash together with a sash-starter and holder constructed in accordance with this invention, the cover being removed, and the window-frame being shown in section, and

20 Fig. 2 shows the same with the parts operated to start the sash.

This invention comprises a sash starter 25 and holder carried by a window sash which is movable along a window frame, the sash starter and holder, comprising a locking member for coacting with the window frame, and a sash starting member also co-

30 acting with the frame, these two members being movable in a direction in a right angle to each other, and an operating member or lever common to both of said members whereby both are operated upon the single 35 operation of the operating lever, although not necessarily simultaneously operated.

The sash starter member preferably pushes 40 against the sill or the frame. This starter and holder is preferably a unitary structure, which can be applied as a unit to the sash, and includes a casing or housing having a stationary pinch handle and the operating 45 lever is arranged opposite to or in juxtaposition to the pinch handle to be within the grasp of the hand taking hold of the stationary pinch handle, as in the conventional sash lock.

A vertically sliding window-sash 10 is guided on each side by the side rail 11 of a

window-frame, and when closed engages a 50 ledge on the sill 12 of the window-frame. At each of the lower corners of the sash is a plate 13 which carries a vertically moving sash-starting member 14 in position to engage the sill of the window-frame. An 55 angle lever 15 is pivoted to the plate and has one arm in engagement with the sash-starting member and is engaged by one end of a hand-lever 16 which is also pivoted to the plate. The point of engagement between the two levers is midway between their pivot points. The distance from the pivot point of the hand-lever to the point of engagement by the hand is two and one-half 60 times the distance from the pivot point of the angle lever to the point where it engages the sash-starting member, and the distances from the two pivots to the point of engagement between them being equal, it follows that relative movement to the sash 65 of the point on the hand lever where force is applied and of the sash-starting member is two and one-half to one, but since the sash rises and carries upward the lever to which upward force is applied, it follows 70 that the total mechanical advantage is three and one-half times. However, these precise proportions are not essential.

The angle lever also carries a sash-holder 75 17 which is adapted to engage holes 18, 18 80 in the side rail and hold the sash at various heights, and the sash-holder is retracted concurrently with the operation of the sash-starting member, the same handle serving 85 for the operation of both.

The parts will return after operation by gravity but preferably a spring 19 is provided to insure the return and to prevent rattling. The mechanism is covered by a 90 plate 20.

I claim,—

1. The combination with a window frame and a window sash, of a sash starter and holder carried by the sash and comprising a lock member coacting with the frame, a 95 starting member movable in a direction at an angle to the lock member and coacting with the sill of the frame, the lock member

being connected to the starting member to actuate it and a pivoted operating member connected to the lock member to operate it.

2. The combination with a window frame and a window sash of a sash starter and holder carried by the sash and comprising a movable lock member coacting with the frame, a starting element movable in a

direction at an angle to the lock member coacting with the sill of the frame, a pivoted operating member coacting with the lock member and one of said members also coacting with the starting element to actuate it. 10

EDWARD E. KRAYN.
